UNITED STATES PATENT OFFICE.

FRANK N. PERRIN, OF DETROIT, MICHIGAN.

PROTRACTOR DRAWING INSTRUMENT.

Application filed March 26, 1926. Serial No. 97,547.

The object of my invention is to provide a combination drawing tool that will readily adapt itself to the several requirements of fundamental drafting.

5 Another object is to combine a protractor and scale, in such a manner and by such means, so as to make it a convertible tool for either a protractor, triangle, scale, curve, or compass.

10 A further object is to produce a drawing instrument that will operate and register with approximate accuracy, for high school and elementary drawing, that is easily operated and can be manufactured at a very low

15 cost.

These several objects are attained in the preferred form by the construction and arrangement of parts more fully hereinafter set forth.

20 Similar parts on all drawings are marked by similar numerals.

Fig. 1 is a plan view of my device showing the general arrangement and combination of parts.

25 Fig. 2 is an edge view of the device showing the relative position of the protractor member to the scale and the connecting member.

Fig. 3 is an alternate form of the protractor member, showing the center portion thereof converted in to the formation of natural curves.

I will now describe more fully the detailed construction of my device, referring to the drawings and the marks thereon.

In general my device comprises a protractor member, fully graduated around the perimeter, in degrees as ordinarily used on protractors. The member being provided with slotted means for attaching thereto, a slotted scale, and in such a manner that the scale may be placed in any desired position on the protractor member, and fixedly attached thereto by a pointed sliding pivot.

45 The scale being so designed and arranged as to operate as a triangle or compass.

The protractor frame —1— is semi-circular in form, having on the diameter thereof a straight edge —11— graduated in even inches. The protractor frame is preferably made of thin celluloid sheet, having degree graduations —2— along the under side of the frame around the circumference thereof, as is the common practice for protractor instruments. A series of numerals shown at —3— and —4— extending around the perim-

eter indicate the number of degrees registered thereon from zero to one hundred and eighty degrees, and numbering in both directions on the protractor scale. It is known, however, that the above method of indicating degrees for protractors is old and in common use, but merely enumerate same to more clearly illustrate their application in my special combination and the operation 60 of my device. The center portion of the frame —1— may be cut out in a semi-circular form as indicated by the curved line —5— and the straight line —6— of Fig. 1, or it may be formed with irregular shaped 65 openings —7—, —8—, —9—, and —10— as illustrated in the Fig. 3, providing a series of irregular curves used in drawing and design work. Near the straight edge —11— of the protractor frame —1—, is formed a 70 narrow slotted recess —12—, positioned parallel to the edge —11— of the frame, and extending nearly across the frame member. Also in the edge —11—, at the center point 75 of the protractor frame —1—, is formed a 75 V-shaped notch —13—, indicating the exact center of the protractor circle and the degrees registered thereon. The edge —11— of the frame is graduated in inches and fractions 80 of inches, as indicated by the marks —17— 85 across the entire diameter of the circle, and bearing lines of figures —19— and —20— thereon for indicating the number of inches registered, the same being numbered in both directions, the length of the diameter line 90 being made in even full inches. Pivots 90 attached to the protractor frame slot —12—

is a thin slotted scale member —14—, also of transparent material, and is provided with a narrow slotted recess —15— along its 95 centerline, nearly the entire length thereof. The scale —14— is provided with an indicating arrow point —16— at one end, positioned on the center line of the scale, also both edges of the scale —14— are graduated 100 into inches and fractions of inches by the fine lines —18— cut thereon, and in the same manner as the scale graduations —17— on the protractor edge. The gradations —18— along both edges of the scale member —14— are marked with lines of numbers —21— indicating the inch marks thereon, but beginning with next to the last number used on the protractor frame in lines —19— and —20—, and continuing the numbering 110 to the end of the scale, the lower number on the scale —14— being placed at the arrow

end thereof, forming thereby an extended rule in combination with the straight protractor edge. Slidably mounted in the slot —12— is a pivot center —22— and which engages with the slot but is free to move therein, said pivot being provided with a sharp pointed projection —23— which projects from the bottom side. The pivot body —27— being cylindrical in form and threaded, passes through and engages the slotted recess —15— of the scale —14—, allowing the scale to be moved at will thereon, and is provided with a washer —24— and operating nut —25—. The nut —25— being threaded to the pivot body and provides means for firmly attaching the scale —14— to the protractor frame —1— in any desired position. The pivot member —22— is formed with a flattened section —26— for engaging the slot walls —12— and preventing the pivot from turning therein, as the nut is tightened thereon. Upon loosening the nut —25—, the scale —14— may be moved to any position on the protractor frame and firmly clamped thereto. Both slots —12— and —15— are so arranged and positioned that when the pivot —22— is moved to the extreme end of the slot —12— of the protractor frame, indicated at the point —A— in Fig. 1, the scale —14— moved thereon to the extreme end of its slotted recess —15— on the arrow end of said scale, as indicated by the dotted lines —B— of Fig. 1, the numbers on both the graduations —17— and —18— will read successive and continuously from zero to the end of the scale, the scale —14— being adapted to operate from either side of the protractor frame —1—, the lower edge of the protractor frame and the scale member —14— forming a continuous straight line when the scale is extended thereon. At the end of the scale —14—, opposite to the arrow end of the scale, is formed a small hole —28—, designed for engaging a pencil point therein for describing circles about the pivot —22—, as the sharp pivot point —23— engages adjacent supporting material, as when placed on a sheet of paper, and the point —23— pressed therein, converting the instrument into a compass. The diameter of the circle described may be varied by sliding the scale under the connecting pivot center —22— before tightening the nut —25— thereon. For forming a triangle of any desired angle, the scale —14— is adjusted over the protractor frame —1—, placing the arrow point —16— over the graduated degree mark along the circumference of the protractor circle, and placing the centerline of the scale slot —15— over the center point —13— of the protractor frame. The pivot —22— being adjusted in both slots —12— and —15— at their intersections, and tightened by the nut —25—, holding the scale —14— in any de-

sired angle. The lower edge of the protractor frame may then be used as one edge of the triangle and the angularly positioned scale forming the other edge of said triangle, the pivot point —23— at all times acting to hold the instrument in a positive position, or provide a positive center therefor.

Having fully described my protractor drawing instrument, what I claim as my invention and desire to secure by Letters Patent is;

1. A drawing instrument comprising a semi-circular shaped protractor frame with one straight side positioned along the diameter line of the protractor circle, a slotted recess formed near the straight side of the frame, said slot being positioned parallel to the straight side of said frame and extended nearly the entire width thereof, a thin scale member, having a slotted recess nearly the entire length thereof, attached to the protractor frame by a central pivot engaging the slots of both the scale and protractor, said pivot provided with means for locking the said scale in any desired position on the protractor frame, also having a sharp engaging point projecting from the bottom side of the pivot for engaging a supporting sheet to establish a center point thereon, and the scale being provided with a pencil hole in one end thereof for describing circles about said centerpoint.

2. A drawing instrument comprising a combination of a semi-circular shaped protractor frame, same being one half of a circular disc cut on a diameter line, and having a straight slotted recess formed near the diameter line and parallel thereto, said slot extending nearly the entire width of the protractor frame, the circular section of said frame being graduated in degree, and the straight side of the frame being graduated into inches and fractions thereof, a thin straight scale member, graduated in inches along both edges thereof and provided with a narrow slotted recess along its center line for nearly its entire length, mounted on said protractor frame by means of a common pivot engaging both of the slotted recesses, said pivot having means for firmly clamping the frame and scale together in any desired position, and also provided with a sharp projecting point on the bottom side of the pivot, said scale being provided with a small hole in one end thereof for engaging and receiving the point of a pencil for describing circles about the pivot point when the point is engaged plane surface.

3. A drawing instrument comprising a semi-circular shaped protractor frame made of thin transparent material, said frame being one half of a circular disc and of even inches in diameter, graduation marks in degrees formed on the under side of the disc protractor frame about the circumference

thereof, also graduation marks formed along the straight edge of the frame arranged in inches and fractions thereof, a slotted recess formed in the frame near the straight edge and parallel thereto, a pointed pivot member fitted into said slotted recess and slidable therein, a flat scale member, having a slotted recess formed along its center line for nearly the entire length thereof, fitted over said pivot through its slotted recess, said scale member being provided with graduation marks along both edges thereof indicating inches and fractions thereof, means for clamping said scale on the protractor frame in any desired position, and said scale being provided with a small pencil hole in one end thereof for describing a circle about the pointed pivot member therein.

4. A drawing instrument comprising a semi-circular shaped protractor, graduated in degrees around the circular section of its perimeter, and graduated in inches and fractions of inches along the straight side of said frame, said protractor being exactly one half of a circular disc cut on a diameter line, a straight slotted recess formed through said

frame near its straight edge and parallel thereto, said slot extending nearly across the frame, a sharp pointed pivot member engaging said slot and slidable therein, a thin scale member bearing graduation marks along both edges thereof indicating inches and fraction of inches, and having a slot formed along its center line, engaging said pivot through the scale slot, means attached to said pivot for clamping said scale to the protractor frame in any desired position, said slots being so arranged and limited that when the scale is extended to draw the pivot into the extreme ends of both slots, said scale being in an alignment with the straight edge of the protractor frame, the inch graduation marks of both protractor and scale will coincide, and the numbers indicating the inches will read consecutively, said scale being provided with an indicating arrow at one end and with a small hole at the opposite end thereof, the hole being positioned on one of the inch graduation marks.

In witness whereof I sign these specifications.

FRANK N. PERRIN.
